RETURN TRAP

Filed Aug. 9, 1928

UNITED STATES PATENT OFFICE

JOHN FRASER, JR., AND FRANK HUTCHINSON, OF MILWAUKEE, WISCONSIN, ASSIGNORS
TO MILWAUKEE VALVE COMPANY, OF MILWAUKEE, WISCONSIN, A CORPORATION OF
WISCONSIN

RETURN TRAP

Application filed August 9, 1928. Serial No. 298,567.

This invention relates to certain new and useful improvements in return traps and refers more particularly to that type of trap especially adapted for use with boilers of

heating systems.

In heating systems of the steam, vapor, and the like types, it is customary to provide a return trap to equalize the pressure within the return line piping and the boiler; and 10 this invention has as one of its objects the provision of a return trap of the character described in which the operating parts are positively actuated and not dependent upon springs.

15 Another object of this invention resides in the provision of a return trap of the character described in which the operating mechanism is wholly enclosed within the receptacle or body of the trap.

20 And a further object of this invention resides in the provision of a return trap for boilers in which a vent valve and a steam valve are coordinated to open one while the other is being closed, gravity actuated means 25 moving the valves, and the rise and fall of a float governing the operation of the gravity actuated means.

With the above and other objects in view which will appear as the description proceeds, our invention resides in the novel construction, combination and arrangement of parts substantially as hereinafter described and more particularly defined by the appended claims, it being understood that such 30 changes in the precise embodiment of the herein disclosed invention may be made as come within the scope of the claims.

In the accompanying drawings, we have 40 illustrated one complete example of the physical embodiment of our invention constructed according to the best mode we have so far devised for the practical application of the principles thereof, and in which:

45 Figure 1 is a transverse sectional view, taken through a return trap embodying our invention, the parts being illustrated with the steam valve closed and the vent valve open;

50 Figure 2 is an enlarged, fragmentary view

similar to Figure 1 illustrating the parts in the opposite position, and

Figure 3 is a sectional view taken on the plane of the line 3—3 of Figure 2.

Referring now more particularly to the accompanying drawings, in which like numerals designate parts throughout the several views, 5 is a fluid receptacle or body having an inlet pipe 6 threaded in an aperture 7 formed in its bottom wall, which connects the receptacle with the return line piping of a heating system, not shown, the water returning from the system rising up into the receptacle as is customary. A cover member 8 is secured to the flanged upper end 60 of the receptacle by cap screws 10 and is provided with a steam inlet port 12 with which a pipe 13 communicates to connect the port with the supply main of the heating system, not shown. A vent port 14 is also formed 65 in the cover member and has a pipe 15 connected thereto to connect the port with an air outlet valve, not shown.

The lower or inner face of the cover 9 is provided with a boss to which the flange 16 75 of a mounting member is secured by cap screws 17, the mounting member having downwardly projected spaced arms 18, the outer ends of which pivotally mount the actuating mechanism of a vent valve 19 and 80 a steam valve 20. The valves 19 and 20 cooperate with valve seats 21 formed at the lower periphery of apertures 22 in the flange 16 of the mounting member and align with the ports 14 and 12 respectively. Each valve 85 has a stem 23 formed integral with or otherwise secured thereto, the upper end of which extends into the adjacent flange apertures to guide the valve and the lower end thereof being positioned between the arms 24 of a 90 bifurcated lever member 25 to which it is pivotally connected, as at 26. The lever member 25 is positioned between the arms 18 of the mounting member and is pivotally 95 connected therewith by a pivot pin 27 located medially of the pivotal connections 26, whereby movement of the lever member 25 coordinates the operation of the valves 19 and 20 to close one as the other opens and vice versa.

One end of the lever member 25 is elongated and directed laterally to provide a finger 28, which is engaged by the arms 29 of an A shaped trip fork 30, pivotally mounted adjacent its apex by the pivot pin 27. A weight 31 is carried by the trip fork adjacent its apex and its position with respect to the pivot 27 and the arms 29 is such that when the vent valve 19 opens and the steam valve 20 closes, as illustrated in Figure 1, the center of gravity of the weight and trip fork moves to the left of the vertical center line of the pivot 27 to engage its upper arm 29 with the finger 28 of the lever 25 and maintain the valves in this position by gravity.

Pivotal connected with the lower arm 29 of the trip fork at a medial point 32 is a rod 33 on which a float 34 is freely slideable to rise and fall with the level of the fluid within the receptacle; the lower portion of the rod 33 being guided in an aperture 35 formed in a cross bar 36 extended across the aperture 7 and having a stop member 37 suitably secured thereto to limit the downward movement of the float 34.

Upwardly extended from the arms 24 of the lever member directly above the pivotal mounting 27 is a pair of upstanding spaced arms 38 carrying a stop member 39 between their outer ends which has a tip or projection extended therefrom to receive one end of an expansile spring 40. The other end of the spring engages a like member 41, mounted between the arms 18 in vertical alignment with the axis of the pivot 27, the spring being in compression at all times. As the arms 38 extend at right angles to the lever member, the ends thereof, during periods of rest of the parts, are either to one side or the other of an imaginary line drawn through the pivot 27 and member 41, depending upon the position of the valves, which permits the energy of the spring to aid the weight in maintaining the parts thus, the spring also taking up all wear on the moving elements. If desired a water column 42 may be provided to display the fluid level within the receptacle.

The operation of the return trap is simple and positive, as when the heating system with which the trap is used is operating under a very low pressure, or under atmospheric pressure only, the trap acts as a receiver and air vent, but when the boiler pressure increases the fluid level within the trap rises and with it the float 34. As the float rises its upper portion abuts the outer extremity of the lower arm of the strip fork, raising it to tip the center of gravity of the weight 30 to the right side (with respect to Figures 1 and 2) of the vertical center line of the pivot 27. The weight then drops to its opposite position, engaging the lower arm of the fork with the finger 28 of the lever member, actuating the same to close the vent valve 19

and open the steam valve 20. The pressure in the boiler and the trap is then equalized and the fluid within the receptacle falls by gravity back into the boiler without collecting in the return mains or risers regardless of the boiler pressure. As the fluid within the receptacle is discharged, the float drops to the bottom of the trap abutting the stop 37 and again opening the vent valve and closing the steam valve, this action being repeated as long as there is a differential in the pressure between the boiler and the return line piping.

From the foregoing description, taken in connection with the accompanying drawings, it will be readily apparent to those skilled in the art to which an invention of this character appertains that we provide a return trap for boilers in which the actuating means are positive in operation, not dependent upon springs and in which the elements are wholly enclosed within a receptacle.

What we claim as our invention is:

1. In a return trap, a fluid receptacle, a cover member for the receptacle having a pair of ports, a mounting plate on the inner wall of the cover member and having openings aligned with and providing valve seats for the ports, valves for said ports, an arm projected from the mounting plate between said ports, a member pivotally mounted from said arm and pivotally connected with the valves whereby one is closed while the other is open, and a substantially A shaped fork member pivotally mounted from said arm in axial alignment with the pivotal mounting of said member connecting the valves, an abutment carried at one end of said member connecting the valves, the ends of the A shaped fork member being disposed on opposite sides of said abutment and engageable therewith to move the member connecting the valves about its pivotal mounting to impart a corresponding movement to the valves, a weight connected with the fork member for maintaining the same in either of two positions, and a float connected with the fork member for moving the same.

2. In a return trap, a fluid receptacle, a cover member for the receptacle having a pair of ports, a mounting plate secured to the underside of the cover member and having openings providing valve seats for said ports, valves for the ports engageable with said seats, an arm disposed between the openings forming the valve seats and extending downwardly from the mounting plate, a member pivotally mounted at the outer end of the arm and connecting the valves whereby one is closed while the other is open, co-operating means carried by the arm and said member for yieldably maintaining said member in either of two positions, one end of said member being extended, and offset to form an abutment, a substantially A shaped fork

member pivotally mounted from the outer end of the arm in axial alignment with the pivotal mounting of said member, the ends of the A shaped fork member being disposed on opposite sides of said abutment to engage the abutment and move the member connecting the valves to and from its two positions, a weight mounted at the apex of said A shaped fork member and adapted to pass to either side of a vertical line drawn through the pivotal mounting of the fork member to hold the fork member in either of two positions by gravity, and float means for moving the fork member.

15 3. In a device of the character described, a receptacle having a pair of ports, valves for the ports, a member connecting the valves, a member having spaced arms one lying on each side of a part carried by the member connecting the valves, a common pivot pin pivotally mounting the member connecting the valves and the member having spaced arms for pivotal movement about a common axis, said pivot pin mounting the member connecting the valves at a point between the valves so that pivotal movement of said member simultaneously opens one valve and closes the other, a weight carried by the member having spaced arms for retaining the same in either of two positions engaging either one or the other of its arms with said part carried by the member connecting the valves, and a float connected with the member having spaced arms and operable to move the same from one position to another, movement of said member having spaced arms in one direction moving the member connecting the valves in one direction and movement of the member having spaced arms in an opposite direction moving said member connecting the valves in an opposite direction whereby the float controls the position of the valves.

40 In testimony whereof we hereunto affix our signatures.

45 FRANK HUTCHINSON.
